UNITED STATES PATENT OFFICE.

HUGH W. KIMES, OF DAYTON, OHIO, ASSIGNOR TO THE VAILE-KIMES COMPANY, OF DAYTON, OHIO, A CORPORATION OF OHIO.

WATER-SUPPLY SYSTEM.

1,247,544.

Specification of Letters Patent. Patented Nov. 20, 1917.

Application filed February 5, 1916. Serial No. 76,327.

To all whom it may concern:

Be it known that I, HUGH W. KIMES, a citizen of the United States, and residing at Dayton, in the county of Montgomery and 5 State of Ohio, have invented new and useful Improvements in Water-Supply Systems, of which the following specification is a full disclosure.

This invention in particular relates to 10 automatically controlled water supply systems, primarily for domestic water service wherein the water from a static water supply source is pumped into a compression tank as a shortage supply under pressure 15 converting the static water in the tank to dynamic form at the fixtures or service outlets.

An object of the invention is to combine 20 such pneumatic water supply system with a direct pump pressure service or branch rendering the pumping apparatus and automatic controlling device of the pneumatic water supply service available for auxiliary purposes and uses to furnish a supply of 25 fresh water direct from the main supply source or well, so that a joint or independent service of either can be had.

Another object of the invention is to provide 30 a water supply system including a storage tank and connected pumping apparatus for maintaining the tank water supply with means interposed and communicatively connecting with the piping system between the pumping apparatus and tank, providing 35 a branch circuit for a direct pump pressure supply water service and a check for said tank against a drawing counterflow of water, but non-interfering with the operation of the pressure actuated motor controlling 40 devices.

Another object of the invention is to provide 45 a local or house water supply system, comprising a compression tank, service pipes for supplying water from said tank, pumping apparatus for supplying water to said tank and maintaining a service pressure in said tank, pressure influenced devices for automatic control of said pump apparatus and relief devices operating under varying 50 pressure influences for preventing or relieving any excessive system pressure or over-load to protect the parts against injury.

Various other features relate to the 55 various parts of the system for automatic and safety control and for different water sup-

ply service, all more fully revealed in the description of the accompanying drawings, illustrating a preferred embodiment of several of the devices and as combined in a system, and as to the system diagrammatically shown, and in such drawings like characters of reference denote corresponding parts throughout the several views of which:—

Figure 1 is a side elevation of an improved automatic pneumatic water supply system, showing a fresh water or direct pressure branch intermediate the pump and storage tank. Fig. 2 is a central vertical section of a relief valve used in the system. 70 Fig. 3 is a central section of a by-pass fitting and check valve. Fig. 4 is a similar view to Fig. 3 of a modified form of valve, showing the valve in open position. Fig. 5 is a central vertical section through the pump, 75 illustrative of valve means for admitting air into the pump and system when the pump is in operation.

Referring to Fig. 1 of the drawings, 1 indicates a pump mounted upon a support 2 and connected to a water supply source by means of the piping 3, and in series including an air chamber fitting 3'. The pump is driven by an electric motor 4 connected by a belt 5 with the fly wheel 6 of the pump. The motor is controlled by a switch device operating under the influence of the pressure in the system for starting and stopping the motor. The electric switch mechanism may be of any well-known type, and detail description of its working parts need not be herein included. The switch mechanism connects with the system piping through a pipe 7 and the switch is contemplated to operate after the supply and pressure in the storage tank 8 has been reduced to a determined degree for starting the motor and pump, and permitting the same to continue in operation until a predetermined storage supply and pressure is again restored. Any form of pump and automatically controlled power apparatus may be used in the water supply system within the aspect of this invention, and as such apparatus is well-known in the art, detail description thereof is not deemed necessary herein. The pump 1 connects with the tank 8 through the piping 9 for supplying water to the tank under the pressure of the pump and 10 represents the pip-110

ing connecting with the tank 8, as a service supply line leading to the various outlets. As the system has primary use as a domestic water supply outfit, the tank is of a capacity to meet the usual water consumption requirements for a given period, without calling for a continued operation of the pumping apparatus, and the tank is essential to the successful operation for maintaining a constant pressure to the service outlets. The water in the tank sometimes remains in storage for a sufficient period to raise its temperature above that directly furnished from a supply source, which is due to a small consumption of the water in storage, and therefore it is sometimes desirable to have a fresh water supply independent of the tank, which may be also utilized as a direct outlet for a continued consumption of water, without exhausting the storage supply, and supplied under direct pumping pressure, and for the purpose herein termed "cold water supply" branch.

In pneumatic water systems of this class under automatic control it is desirable for the safety of the system to install a relief valve 11 connected in series with the pipe system 9 leading from the pump to the storage tank. The relief valve 11 is controlled by the influence of the varying pressure in the system, opening to relieve or prevent any excessive system pressure and an escape of the water supply from the pump principally due to the continuing operation of the pump by reason of automatic switch or motor controlling devices failing to promptly respond to an effective or influencing degree of pressure.

A preferred type of relief valve is shown herein as one especially adapted to the particular use, arranged to quickly respond in its movements to full open or closing, and avoid any sluggish valve operation, which may cause an excessive degree of pressure in the system, overload or damage to the system apparatus. This preferred type of relief valve is made the subject-matter of a separate application filed of even date herewith, Serial No. 76,325, and to which reference should be had for a more comprehensive disclosure than contained herein. In the system herein the relief valve preferably is installed intermediate the storage tank and cold water supply branch.

55 *Fresh water or continued supply branch.*

In providing a fresh water or continued supply branch in connection with a pneumatic water supply system, including the storage tank and providing a supply independent of the storage tank, I provide water check devices in series with a piping between the pumping apparatus and tank, non-interfering to the pressure influence devices, but capable of approximately check-

ing a counterflow or escape of the storage water supply in the tank. A combined bypassing water check fitting 13 placed in series with the system piping between the pump and tank, and in its preferred form of construction comprises a body 14, as a pipe coupling providing a water check valve intermediate thereof. A web 15 extends interiorly across the chamber of the body to divide the same and is provided with a valve-seat-equipped opening, having a seat ring 16 fitting therein with the axis preferably in a vertical plane to permit the valve to operate by gravity. The body has a hub extension 17 providing an opening into the body and coaxial with the valve opening for receiving the guide plug 18. 19 indicates a valve which may be constructed either as shown in Fig. 3 or in the modified form shown in Fig. 4, the latter being preferable. In the form shown in Fig. 3 the valve has the guide wings 20 projected from its upper face slidably fitting an orifice in the guide plug 18. The opposite face of the valve has the guide wings 21 projecting therefrom, which guide the opposite side of the valve within the seat ring, the valve closing toward the inlet side and under the influence of the pressure from the tank side, lifting or opening under the pumping pressure when supplying the tank. In order to equalize the pressure upon both sides of the valve and not interfere with the pressure controlled devices for starting the motor or relief valve, the valve is apertured as at 22, Fig. 3, or notched as shown at 23, Fig. 4, to provide a restricted passage affording communication between opposite sides of the valve when closed for equalizing the pressure upon both sides of the valve. The valve is operated or controlled under the influence of the prevailing pressure upon either of its sides, for opening or closing, and when the prevailing pressure is on the system or tank side the valve will be closed and approximately prevent the water from escaping in a counter direction.

The body 14 has a hub extension 24 forming a by-passing nipple, for making the fresh water supply connections, as pipe 25, for a direct fresh water supply branch extending to service point desired with the delivery capacity of the pump, and provided with suitable valves or cock controlled outlets. The drawing shows the pipe 25 extended upwardly and provided with a cock 26 for sealing the branch when not in use, which is necessary so as not to interfere with the normal operation of the system. As shown in Fig. 4, the valve 19 is provided with a stem 27 slidably fitting the bore of the guide plug 18, which in the upward movement of the valve compresses the air in the cap plug 18 to assist in closing the valve.

The upper face of the valve is also pro-

vided with a stop lug 28 to limit its opening motion and prevent its face from coming in contact with the surface of the guide plug 18, or possibly adhering thereto and exposing only one side of the valve to the tank pressure, abnormally holding the valve open.

5 In operation let it be assumed that the tank has been filled to its capacity and under a predetermined pressure which will automatically stop the pumping apparatus and permit the valve 19 to seat. Should it however be desirable to have the supply of fresh water, as for drinking purposes, the valve 26 of the fresh water supply branch is opened, 10 which immediately lowers the pressure in the piping 9 between the check valve 13 and the electric switch mechanism 29 functioning the switch, starts the motor and operates the pump, forces the water through the pipe 25 and service outlet. The pumping apparatus 15 continues in operation during such service period.

Upon closing the valve 26, the pressure in the system piping or service line is increased 20 to the degree which influences the switch devices for throwing the pumping apparatus out of commission, provided there has been no appreciable loss or reduction in the tank pressure, or consumption of the static 25 water supply, and if so such is restored before the pumping apparatus stops.

The fresh water branch enables the user to get an abundant supply of fresh cool water direct from the well, at will, for either 30 drinking, cooking or household purposes, or for a more continued water consumption, as lawn sprinkling, without interfering with a normal static water supply connecting with the various fixtures in the house. The supply 35 in the storage tank may during the direct fresh water consumption period be regarded as a reserve for instances when an unusual demand is required beyond the delivery capacity of the size pump installed.

45 System air supply.

To maintain the water in the compression tank in a dynamic form at the fixture, or to prevent water-logging of the compression 50 tank and to maintain such air supply, air intake means in combination with the pump are provided. The air is drawn into the pump on a suction stroke of one side of the pump-piston and on its reverse or power 55 stroke forced with the water into the tank. I am aware that it is well-known in the art to provide a pump with air intake devices, but the devices herein are very efficient, simple and easily regulated and essential to the 60 system as an automatically controlled outfit for supplying water.

In Fig. 5 I have illustrated a central vertical section of the preferred type of pump for the system above described, having the 65 air intake attachment connected into the cyl-

inder head or cap. The pump comprises the chest or casing 30, cylinder 31, piston 32 sliding in the cylinder, suction valves 33 and discharge valves 34, 35, indicates a cylinder head or cap screw-threaded into the chest or pump casing 30 which is tapped to receive the air intake attachment for admitting air into the passage or chamber 36 of the pump, between the suction and discharge valves. Air is drawn into said chamber during a 75 suction or forward stroke of the piston relative to said chamber or passage 36. During a reverse stroke of the piston the air with the water in said pump passage or chamber 36 is forced through the opening controlled 80 by the discharge valve 34 and into the system line and tank.

The air intake attachment consists of a body member 37 having an integral laterally projected nipple 38 tapped to connect with the cylinder head 35, and an integral shank portion 39 bored to receive the needle pointed valve 40. 41 indicates an air inlet port communicating with the valve chamber 42, said valve chamber 42 communicating with a 90 second valve chamber 43 through a restricted port 44. This needle valve 40 seats against the edge of the port 44 for controlling or regulating the volume of air admitted with each air intake stroke of the piston. A ball valve 95 45 as a check is housed within the second valve chamber 43 and seats against the edge of the passage bore 46 and confined within the annular flange 47 of the plug 48, for stopping the air opening through the body 100 leading into the second valve chamber. The ball valve checks or closes against any escape of products from the pump passage 36 on the power stroke of the piston for said passage 36.

105 I claim:

1. A water supply system, combining service supply pipes including a compression tank in series for supplying water to the place of utilization, a pump connected with a source of water and with said supply pipes, motor devices for operating said pump, pressure controlled means connecting with said service pipes influenced by different degrees of pressure in said piping, for 110 controlling the operation of said motor devices, a direct pump service branch connecting with said service pipes, and water check devices interposed in said pipes beyond said direct pump service branch to withhold an 115 ineffective counterflow of water and non-im peding for establishing a pressure equilibrium with the non-use of said branch for motor control.

2. A water supply system combining a 120 compression tank for receiving water and supplying it to the place of utilization, water pumping apparatus connected with said tank for supplying water thereto, pressure actuated devices influenced by the pressure 125

in said tank for controlling the operation of said pumping apparatus, a direct pump water service branch connected intermediate 5 the pumping apparatus and tank controlling the pressure in the line to said pressure actuated devices, and an automatically actuated valve interposed in the connection between direct pump service branch and tank as a check against a tank draining counter- 10 flow of water from said tank, and providing a restricted passage around said valve when closed for normally maintaining a pressure equilibrium in said pipes.

3. A water supply system combining a 15 compression tank for receiving and supplying water to the place of utilization, water pumping apparatus connected with said tank for supplying water thereto, a direct pump water service branch in connection 20 with the line connecting said pumping apparatus and tank, pressure actuated devices operating upon determined changes in pressure in said tank and direct pump service branch, for controlling the operation of said 25 pump apparatus, and a water check device for withholding a tank draining counterflow of water.

4. A water supply system combining a 30 compression tank for receiving and supplying water to the place of utilization, water pumping apparatus connected with said tank for supplying water thereto, a direct pump water service branch in connection with the line connecting said pumping apparatus and tank, pressure actuated devices 35 operating upon determined changes in pressure in said tank and direct pump service branch for controlling the operation of said pump apparatus, a water check device for withholding a tank draining counterflow of water, and pressure relief means in connection 40 with said pipes and tank providing for the escape of water under abnormal pressure conditions.

45 5. A water supply system combining a compression tank and piping for receiving and supplying water to the place of utilization, water pumping apparatus in connection with said tank for supplying water thereto, pressure actuated devices influenced 50 by different degrees of pressure in said piping and tank for controlling the opera-

tion of said pumping apparatus, a water check valve and pipe coupling member interposed in the piping to said tank, comprising a hollow valve casing, having an interior division wall with a valve-seat equipped opening therethrough for passage continuity through the casing, a valve for reducing said opening area to a restricted 60 passage to approximately withhold a tank draining counterflow of water, said casing provided with a by-pass opening for a direct pump water service connection beyond the control of said valve. 65

6. A water supply system combining a compression tank for receiving and supplying water under pressure to service piping, a pump for supplying water to said tank, an electric motor for operating said pump, 70 pressure actuated switch devices for starting and stopping said motor operated by different degrees of pressure in said tank, a branch service line connecting with said pump and said pressure actuated switch devices, and a check valve in the inlet line to said tank having a restricted constantly open port, whereby in the control of said branch the pressure in the line to said pressure actuated device will be varied for operating said 80 device for a direct pump service through said branch. 75

7. A water supply system combining a compression tank for receiving and supplying water under pressure to the service 85 piping, a check valve in the inlet line to said tank having a constantly open port therethrough, a pump for supplying water to said tank, a motor for said pump, a pressure actuated device for starting and stopping said motor actuated by the pressure in said system and tank, and a branch service line connecting with said pump line to the tank at the pump side of the check valve, whereby the control of said branch will vary 90 the pressure to said pressure actuated device for a service supply independent of the tank. 95

In witness whereof, I hereunto subscribe my name, as attested by the two subscribing witnesses.

HUGH W. KIMES.
